UNITED STATES PATENT OFFICE

FRANK X. ENDERLE, OF LOS ANGELES, CALIFORNIA

DESIGN FOR AN INCINERATOR

Application filed September 23, 1929. Serial No. 32,842. Term of patent 7 years.

To all whom it may concern:

Be it known that I, FRANK X. ENDERLE, a citizen of the United States, residing at Los Angeles, in the county of Los Angeles and State of California, have invented a new, original, and ornamental Design for an Incinerator, of which the following is a specification, reference being had to the accompanying drawing, forming part thereof.

The figure is a perspective view of an incinerator showing my new design.

The base ornamentation is continuous around the figure, while the back is substantially plain and smooth except for the normal lines occurring in the folds of the dress.

I claim:

The ornamental design for an incinerator, substantially as shown and described.

FRANK X. ENDERLE.
